Des. 239,414

Patented Mar. 30, 1976

239,414

COMBINED SLIDE PROJECTOR AND MAGAZINE THEREFOR

Serge Besancenot, 38 Quai de Jemmapes,
Paris 10, France

Filed Mar. 28, 1973, Ser. No. 345,755

Claims priority, application France Oct. 3, 1972

Term of patent 14 years

Int. Cl. D16—02

U.S. Cl. D61—1 J

FIG. 1

FIG. 2

FIG. 1 is a top, front and left side perspective view of a combined slide projector and magazine therefor showing my new design in an exploded open position; and

FIG. 2 is a top, front and left side perspective view thereof in the closed position.

The rear, bottom, and right sides of my design, not shown, are plain and unornamented.

I claim:

The ornamental design for a combined slide projector and magazine therefor, as shown and described.
